STRAINER AND DIRT COLLECTOR

Filed Oct. 6, 1927

UNITED STATES PATENT OFFICE.

MILTON DENNEY, OF TIPTON, MICHIGAN.

STRAINER AND DIRT COLLECTOR.

Application filed October 6, 1927. Serial No. 224,473.

This invention relates to strainers and dirt collectors of the style set forth in my Patent No. 1,632,699 granted June 14, 1927, and it is an object of the invention to provide a device of this kind comprising means to effectively retain separated dirt or the like within the bowl upon creation of back suction as may occur when the device is employed in connection with a railway air brake system and the like.

It is also an object of the invention to provide a device of this kind comprising a collecting bowl into which a straining element extends together with means for protecting such element.

The invention consists in the details of construction and in the combination and arrangement of the several parts of my improved strainer and dirt collector whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawing, wherein:

Figure 1 is a sectional view illustrating a strainer and dirt collector constructed in accordance with an embodiment of my invention;

Figure 2 is a sectional view taken substantially on the line 2—2 of Figure 1;

Figure 3 is a view in top plan of the valve member as herein set forth.

As disclosed in the accompanying drawing, B denotes a body, preferably cast, and substantially T-shaped in elevation and which is provided with two bores or passageways 1 each leading from an end of the head portion 2 of the body and terminating at the lower end of the stem portion 3. The outer portions of the bores or passageways 1 are provided with means, such as internal threads 4, whereby the device in its entirety may be readily interposed within a desired line.

Underlying the stem portion 3 of the body B is a cup member or bowl C, the upper portion of which being partially closed by a plate 5 which provides a relatively large opening 6 with which the inlet bore or passageway 1 communicates. The free edge of

the plate 5 is straight and extending downwardly from said straight edge portion of the plate 5 and inclined in a direction to partially underlie the opening 6 is a plate or flange 7. This plate or flange 7 serves particularly to provide protection for the straining element 8 which extends within the bowl or cup member C through the opening 9 in the plate 5, said opening 9 registering with the outlet bore or passageway 1 of the body. 65

Carried by the side wall of the cup member or bowl C and extending entirely there-around is a continuous plate 10 arranged in the form of an inverted cone having its lower or apex portion open, as at 11, the marginal portion of the plate defining such opening being ground to provide a downwardly facing valve seat 12.

The bottom wall 14 of the cup member or bowl C at a point below the opening 11 is provided with an opening 15 normally closed by a plug 16. Carried by this plug 16 and extending upwardly within the cup member or bowl C and terminating a desired distance below the plate 10, or more particularly the valve seat 12 thereof, is a stem 17 which provides a mounting for the valve structure V.

This valve structure V comprises a conoidal member 18 positioned above and spaced from a second member 19 substantially in the form of an inverted cone with its lower or apex portion open, as at 20. These members 18 and 19 are secured one to the other and maintained in desired relation through the instrumentality of the interposed arms 21. Normally the valve structure is in its open position with the central or apex portion of the member 18 resting upon the upper end of the stem 17. However, upon abnormal suction within the bowl, especially in connection with an air brake system or the like, the valve structure will move upwardly bringing the member 18 in contact with the valve seat 12, thus effectively preventing the dirt or the like collected within the cup member or bowl C being carried out. 95

As the fluid passes into the cup member or bowl C from the intake bore or passageway 1 contact of the same with the continuous plate 10 will result in a portion of the dirt or foreign matter carried by the fluid being drawn through the opening 11 into the lower portion of the cup member or bowl C. The fluid as it passes out through the outlet bore 111

or passageway 1 first passes through the straining element 8 which is of a character to substantially entirely remove from the fluid all remaining dirt or foreign matter. This 5 dirt or foreign matter separated from the fluid drops through the opening 11 upon the upper plate 18 of the valve structure V and from said plate 18 upon the lower plate 19 and will readily drop out through the lower 10 central opening 20 of such plate.

This lower plate 19 comprised in the valve structure V operates to catch the dirt which is within the lower portion of the cup member or bowl C when the air brake is set in emergency as it will serve to keep such dirt from readily passing up over the upper plate 18. This desirable action is further facilitated in view of the fact that the lower peripheral 15 edge of the upper plate or member 18 is substantially midway of the upper and lower edges of the lower plate or member 19.

It is also to be particularly noted that the plate or flange 7 operates to prevent the dirt passing into the cup member or bowl C from 20 coming into direct contact with the straining element 8.

The cup member or bowl C is adapted to be secured to the stem 3 of the body B in any desired manner and herein disclosed through 30 the instrumentality of the bolts 22.

From the foregoing description it is thought to be obvious that a strainer and dirt collector constructed in accordance with my invention is particularly well adapted for 35 use by reason of the convenience and facility with which it may be assembled and operated, and it will also be obvious that my invention is susceptible of some change and modification without departing from the 40 principles and spirit thereof and for this reason I do not wish to be understood as limiting myself to the precise arrangement and formation of the several parts herein shown in carrying out my invention in practice except as hereinafter claimed.

I claim:

1. A combined strainer and dirt collector comprising a body member having disposed therethrough an inlet bore and an outlet bore, 50 a cup member, means for securing the body member and cup member one to the other, the bores of the body member being in communication with the interior of the cup member, a plate partially closing the cup member immediately adjacent to the body member, said plate having an opening communicating with the outlet bore of the body member, a straining element extending within the cup member through the opening in the plate, and a 55 flange carried by the inner free marginal portion of the plate and disposed downwardly toward the peripheral wall of the cup member.

2. A combined strainer and dirt collector 60 comprising a body member having disposed therethrough an inlet bore and an outlet bore, a cup member carried by said body member and with which the bores communicate, a straining element interposed in the outlet

therethrough an inlet bore and an outlet bore, a cup member, means for securing the body member and cup member one to the other, the bores of the body member being in communication with the interior of the cup member, 70 a plate partially closing the cup member immediately adjacent to the body member, said plate having an opening communicating with the outlet bore of the body member, a straining element extending within the cup member 75 through the opening in the plate, and a flange carried by the inner free marginal portion of the plate and disposed downwardly and inclined in a direction to partially underlie the communication between the inlet bore and 80 the cup member, said flange being disposed downwardly toward the peripheral wall of the cup member.

3. A combined strainer and dirt collector comprising a body member having an inlet 85 passage and an outlet passage, a cup member carried by said body member and with which the passages communicate, a straining element interposed in the outlet passage, a partition arranged within the cup member and provided with an opening communicating 90 with the lower portion of the cup member, a normally open valve member of sufficiently light material that suction will close it, said member being arranged within the lower portion of the cup member below the opening and freely upwardly movable upon abnormal suction to close the communication afforded by said opening, and pneumatic pressure drop responsive means for lifting the valve 100 member upwardly into closed position at the partition opening.

4. A combined strainer and dirt collector comprising a body member having an inlet 105 passage and an outlet passage, a cup member carried by said body member and with which the passages communicate, a straining element interposed in the outlet passage, a partition arranged within the cup member and provided with an opening communicating 110 with the lower portion of the cup member, a normally open valve member of sufficiently light material that suction will close it, said member being arranged within the lower portion of the cup member below the opening 115 and freely upwardly movable upon abnormal suction to close the communication afforded by said opening, the marginal portion of the partition defining said opening being formed to provide a downwardly facing valve seat 120 with which said valve member engages, and pneumatic pressure drop responsive means for lifting the valve member upwardly into closed position at the partition opening.

5. A combined strainer and dirt collector 125 comprising a body member having disposed therethrough an inlet bore and an outlet bore, a cup member carried by said body member and with which the bores communicate, a straining element interposed in the outlet

bore, a plate arranged within the cup member and provided with a central opening affording communication with the lower portion of the cup member, a normally open valve member arranged within the lower portion of the cup member and movable to close the communication afforded by said opening, said valve member comprising two spaced plates arranged one above the other, the upper plate being conoidal and the lower plate being substantially in the form of an inverted cone with its central portion open, and an upstanding member carried by the cup member extending through the opening in the bottom plate of the valve member and upon which the upper plate of the valve member normally rests.

6. A combined strainer and dirt collector comprising a body member having disposed therethrough an inlet bore and an outlet bore, a cup member carried by said body member and with which the bores communicate, a straining element interposed in the outlet bore, a plate arranged within the cup member and provided with a central opening affording communication with the lower portion of the cup member, a normally open valve member arranged within the lower portion of the cup member and movable to close the communication afforded by said opening, said valve member comprising two spaced plates arranged one above the other, the upper plate being conoidal and the lower plate being substantially in the form of an inverted cone with its central portion open, and an upstanding member carried by the cup member extending through the opening in the bottom plate of the valve member and upon which the upper plate of the valve member normally rests.

7. A combined strainer and dirt collector comprising a body member having disposed therethrough an inlet bore and an outlet bore, a cup member carried by said body member and with which the bores communicate, a straining element interposed in the outlet bore, a plate arranged within the cup member and provided with a central opening affording communication with the lower portion of the cup member, a normally open valve member arranged within the lower portion of the cup member and movable to close the communication afforded by said opening, said valve member comprising two spaced plates arranged one above the other, the upper plate being conoidal and the lower plate being substantially in the form of an inverted cone with its central portion open, and an upstanding member carried by the cup member extending through the opening in the bottom plate of the valve member and upon which the upper plate of the valve member normally rests, the lower margin of the upper plate being positioned substantially midway of the upper and lower margins of the lower plate.

8. A combined strainer and dirt collector comprising a body member having disposed therethrough an inlet bore and an outlet bore, a cup member carried by said body member and with which the bores communicate, a

straining element interposed in the outlet bore, a plate arranged within the cup member and provided with a central opening affording communication with the lower portion of the cup member, a normally open valve member arranged within the lower portion of the cup member and movable to close the communication afforded by said opening, said valve member comprising two spaced plates arranged one above the other, the upper plate being conoidal and the lower plate being substantially in the form of an inverted cone with its central portion open, and an upstanding member carried by the cup member extending through the opening in the bottom plate of the valve member and upon which the upper plate of the valve member normally rests, and means for connecting the plates for unitary movement to maintain the same in desired spaced relation.

8. A combined strainer and dirt collector comprising a casing, an inlet and an outlet therefor, a strainer between the inlet and outlet, a partition arranged in the casing below the inlet and having an opening, a back suction normally open valve member loosely mounted so it may freely move upwardly to close said opening upon back suction in the casing, and pneumatic pressure drop responsive means for lifting the valve member upwardly into closed position at the partition opening, said member being of sufficiently light material that suction will close it.

9. A strainer and dirt collector embodying a housing having an open side provided with adjacent inlet and outlet ports, there being a baffle for the inlet port and a screen for the outlet port, a partition below the ports determining a chamber in the housing therebelow with an opening from the chamber communicating with the ports, and a closure for the opening of sufficiently light material that suction will close it.

In testimony whereof I hereunto affix my signature.

MILO DENNEY.
